HAIRPIN DISPENSER

Michael Frank and David Willinger, Freeport,
N. Y.

Application September 28, 1936, Serial No. 103,041

3 Claims. (Cl. 312—90)

This invention appertains to new and useful improvements in an apparatus for conveniently dispensing hairpins.

The principal object of the present invention is to provide a hairpin dispenser which will be desirable for use in hair dressing shops where at present the customer is imposed upon to hold hairpins and hand the same to the operator when called for.

Another important object of the present invention is to provide a hairpin dispenser which can be conveniently operated by the foot of the beauty operator whereby hairpins can be delivered to herself singly without additional manual assistance.

These and various other important objects and advantages of the invention will become apparent to the reader of the following specification.

In the drawings:

Figure 1 represents a side elevational view of the apparatus supported by a wall hanger.

Figure 2 is a fragmentary front elevational view of the apparatus.

Figure 3 is an enlarged horizontal sectional view taken substantially on line 3—3 of Figure 2.

Figure 4 is an enlarged fragmentary vertical sectional view through the hopper.

Figure 5 is a fragmentary horizontal sectional view taken substantially on line 5—5 of Figure 4.

Figure 6 is a fragmentary top plan view of the hopper showing the fastening means for the removable side wall.

Figure 7 is a fragmentary perspective view of operating connections presently described in detail.

Referring to the drawings, wherein like numerals designate like parts, it can be seen that numeral 5 represents an elongated vertically disposed hopper, preferably square in cross-section.

40 This hopper is open at its top and provided with the bottom wall 6 which is cut away as at 7 to expose some of the fingers 8 of the feed wheel 9 which has a threaded bore therethrough for receiving the screw shaft 10 which supports the follower 11 at its upper end. This follower supports a quantity of hairpins thereon and access can be gained to the same and the hairpins thereon by the movable side wall 12 which is hinged at its lower end as at 13 to the said bottom wall.

45 6. The bottom wall 6 is provided with the up-standing barrel 14 to guide the screw shaft, while the sub-bottom wall 15 between which and the bottom wall 6 the wheel 9 is operative, has the depending guide barrel 16 through which the screw shaft 10 extends.

Referring to Figure 1, it can be seen that the numeral 17 denotes a small tray having an up-standing back wall 18 on which the permanent magnet 19 is located. An arm 20 pivotally secured to one side of the hopper 5 supports this 5 tray 17 which is magnetized, the hairpin resting between magnet 19 and tray 17 which is magnetized to prevent the hairpin from falling. Numeral 21 represents an elongated substantially semi-circular shaped arm, the upper end of which 10 is provided with the yoke 22 in which the tray 17 is pivotally mounted the lower end of said arm being pivotally secured as at 23 between the ears 24 on the hopper 5. This semi-circular arm 21 is provided with the depending arm 25 which is connected by the pivotal link 26 to the arm 27 the latter being pivoted intermediate its ends, as at 27a, to a bracket 27b extending from the hopper 5.

15 Numeral 28 represents a treadle which is supported by the elongated control rod 29, the same being slidable through the guides 30 and 32 on one side of the hopper 5. An arm 31 extends from the upper portion of the elongated rod 29 and is operatively connected as at 32 to the upper end of the push arm 33 which terminates in the head 34 slidable through an opening 34a in the lower portion of the hopper to engage the fingers 8 on the feed wheel 9.

20 An operating connection is provided between the rod 29 and the link member 27 in the form of 30 an arm 35 extending from said rod 29 and overlying the inner end of the link member as shown in Figure 7 of the drawings. An elongated coil spring 36 extends from the arm 20 to the pivotal connection 37 between the arm 25 and link 36 35 and from said connection 37 the coil spring 38 extends to the pivot 27a of the arm 21.

25 It can now be seen that in the operation, downward movement of the rod 29 by a person's foot on the treadle 28 causes the semi-circular shaped 40 arm 21 to be swung upwardly bringing the magnet 19 over the hopper 5, while at the same time the push rod 33 causes its head 24 to press against one of the fingers 8 of the wheel 9 so as to rotate the wheel sufficiently to cause a slight upward 45 movement of the shaft 10 and the follower 11, the follower 11 pushing the quantity of hairpins thereon upwardly a slight distance. The tray 17 is constructed to pivot by gravity when off the support 20, so that it is not interposed between 50 said magnet and the contents of the hopper 5. Upon release of the treadle 28, the mechanism will resume its position shown in Figure 1, the hairpins probably dropping off onto the tray 17, where it can be easily reached by the beauty shop opera- 55

tor. The tendency of the push rod 33 is to normally align itself with the arm 31 but said rod 33 is sufficiently resilient to permit lateral flexing thereof by the fingers 8 of the wheel 9 such as is required for rotation of said wheel by said rod and the opening 34a is sufficiently large to permit such flexing.

If desired, a suitable wall plate, especially one of tapered design, can be secured to a wall 39 and 10 a wedge-shaped socket structure 40 on one side of the hopper 5 can be engaged with such a wall plate for supporting the apparatus in the manner substantially shown in Figure 1.

Suitable spring fasteners 41 can be employed 15 on the upper end of the hopper so as to engage the hinged side walls 12 and retain the same in closed position as shown in Figure 4.

While the foregoing specification sets forth the invention in specific terms, it is to be understood 20 that various changes in the shape, size, and materials may be resorted to without departing from the spirit and scope of the invention as claimed hereinafter.

Having described the invention, what is claimed 25 as new is:

1. A dispenser for hairpins comprising, a hopper, a feed screw extending upwardly into said hopper, a follower on the upper end of said screw operative by said screw to elevate the contents of 30 the hopper, a toothed wheel at the bottom of the hopper threaded onto said screw and operative

to elevate the same, a magnet swingably mounted at one side of the hopper for movement over the same to attract the contents therefrom, and means for swinging said magnet and operating said wheel including a foot pedal. 5

2. A dispenser for hairpins, comprising, a hopper, a feed screw extending upwardly into said hopper, a follower on the upper end of said screw operative by said screw to elevate the contents of the hopper, a toothed wheel at the bottom of the 10 hopper threaded onto said screw and operative to elevate the same, a magnet swingably mounted at one side of the hopper for movement over the same to attract the contents therefrom and tensioned against such movement, and means for 15 swinging said magnet and operating said wheel including a foot pedal.

3. A dispenser for hairpins comprising a hopper, a feed screw extending upwardly into said hopper, a follower on the upper end of said screw 20 operative by said screw to elevate the contents of said hopper, a toothed wheel at the bottom of the hopper threaded onto said screw and operative to elevate the same, a tray swingably mounted at one side of the hopper for movement into 25 a position over said hopper, a magnet on said tray for attracting the contents of the hopper, and means for swinging said tray and operating said wheel.

MICHAEL FRANK. 30
DAVID WILLINGER.
